UNITED STATES PATENT OFFICE.

RALPH H. WHISLER, OF HALFWAY, AND STUART G. BAITS, OF DETROIT, MICHIGAN,
ASSIGNORS TO ESSEX MOTORS, OF DETROIT, MICHIGAN, A CORPORATION OF MICHIGAN.

STARTING AND LIGHTING DEVICE FOR INTERNAL-COMBUSTION ENGINES.

Application filed October 5, 1921. Serial No. 505,600.

To all whom it may concern:

Be it known that we, RALPH H. WHISLER and STUART G. BAITS, both citizens of the United States, residing at Halfway and Detroit, county of Macomb and county of Wayne, respectively, State of Michigan, have invented a certain new and useful Improvement in Starting and Lighting Devices for Internal-Combustion Engines, of 10 which the following is a specification, reference being had therein to the accompanying drawings.

Our present invention relates to electrical starting and lighting equipment for automobiles or other motor vehicles. The particular object of the invention is to provide a simpler and more convenient mechanism than those heretofore commonly employed; also one which can be put in place more 15 conveniently and rapidly. The equipment embodying our invention is of the double unit type, but it may in some instances be employed to take the place of single unit systems already installed or be used in combination with power plants designed especially for use in connection with single unit sets.

Our invention is employed in connection with an engine having a crank case and a 20 flywheel casing, the flywheel of the engine being provided with gear teeth for engagement with a pinion on the end of the starting motor shaft. We provide a member called a base on which are placed the starting motor and generator and within which are located the switch and a portion of the mechanism by means of which engagement between the starting motor shaft and the flywheel is effected. Within the flywheel 25 casing is placed a train of gears connecting the starting motor shaft with the flywheel gear, and these gears are moved into and out of mesh as is required by a plunger or shaft which also operates the electric switch 30 of the starting motor and which extends through the flywheel casing into the base.

This construction has the great advantage that it may be assembled and lined up with very little effort or skill. To do this, the generator and starting motor are placed on the base, the base is put in place on the crank case, the switch plunger is then inserted through the crank case and the gear

and pinion. These are then secured to the plunger and the bolts, which hold the base in place on the crank case, are then tightened up. Other important features of our invention will be apparent from the following description.

The invention will be fully understood 35 from the following description when taken in connection with the accompanying drawings, and the novel features thereof will be pointed out and clearly defined in the claims at the close of this specification. 40

In the drawings, Fig. 1 is a side elevation of a power plant for an automobile including an internal combustion engine, together with the flywheel casing therefor, to which is applied a starting and lighting 45 set embodying our present invention.

Fig. 2 is a longitudinal vertical section of the starting and lighting set, the base and a portion of the crank case and flywheel 50 casing.

Fig. 3 shows the parts shown in Figure 2 in the position which they occupy just as the gears are about to mesh.

Fig. 4 shows the parts in the position occupied when the starting switch has been 55 closed.

Fig. 5 is a view of the plunger assembly.

Referring now to the drawings, at A is shown the crank case, at B the flywheel casing and at C the engine cylinders. In 60 general, these parts are of ordinary construction and form no part of our invention. At 11 is shown the starting motor and at 12 the generator. The base is designated 13 and rests on a portion c of the crank case, being secured thereto by two bolts 14 and 15. At 16 (see Figs. 2, 3 and 4) are shown the 65 gear teeth on the flywheel.

The shaft 17 of the starting motor carries a pinion 18 which is constantly in mesh with a gear 19 formed on one member of a roller clutch, the other member being a hub 20 forming part of a pinion 21. One roller of the clutch may be seen at 2. The gear 19, pinion 21 and rollers 2 form a single 70 assembly which is rotatable on a bushing 23 and is held in place therein by a collar 6 and set screw 7. The parts are so located that the pinion 21 can be slid lengthwise with the bushing 23 into engagement with 75 the teeth of the flywheel 16. When thus

engaged, the starting motor 11 can drive the flywheel through the pinion 18, gear 19, pinion 21 and the teeth of the flywheel 10. This drive can take place in one direction only, on account of the action of the roller clutch and, therefore, when the engine begins to fire and speeds up so that the pinion 21 is revolving faster than the gear 19, the clutch is disconnected, and the starting motor will not be driven by the engine.

The bushing 23 is mounted on a plunger 24 which is connected by suitable linkage, not shown, to a pedal or hand lever. It is also returned to its normal position by a spring, also not shown. The plunger 24 extends all the way through the flywheel casting B, being supported in a bearing 25. A spiral spring 26 surrounds the plunger which is connected to a switch-operating member 27, the spring being located between the end of the switch-operating member 27 and the end of the bushing 23, so that the bushing 23, gear 19 and pinion 21 are held against the shoulder *a* of the plunger 24. The switch-operating member 27 is of novel construction having a torpedo-shaped end comprising an inclined portion *b*, a flat or cylindrical portion *d* and a conical nose *e*.

The bushing 23, plunger 24, spring 26, and switch-operating member form a separate assembly as will be seen from Fig. 5. Within a compartment *f* in the base 13 is a switch comprising a pair of blades 8 and two contact members 9. The contact members are connected respectively to the battery and starting motor by means of the wires 30 and 31. The switch blades 8 are mounted on a slide 32 movable in the base 13 at right angles to the axis of the switch plunger 24. The slide has on one end a button or head 33. A spring 4 tends to hold the slide with the head in the path of the torpedo on the plunger and to keep the switch open. From the foregoing it will be seen that movement of the plunger to the left causes the head 33 to ride on the inclined surface *b*, closing the switch, and that when the head 33 rides on the flat or cylindrical surface *d*, the spring 4 has no tendency to push the plunger to the right and, therefore, makes it easier for the operator to hold the switch closed during the period when this is necessary. This feature is of particular importance in case, for any reason, the engine starts with difficulty, as it relieves the operator of the fatigue of holding down the starting button against the pressure of the spring 4 for any considerable length of time.

In assembling the equipment embodying our invention with the engine, the base 13 is put in place on the ledge or bracket *c* cast on the crank case, and the pinion 21 and gear 19 which together form an assembly, are inserted with the collar 6 through

the handhole in the flywheel casing B. They are held in proper position and then the plunger assembly (see Fig. 5) is inserted through the flywheel casing from the rear end, being pushed through to its proper position. Then the set screw 7 is put in place. Thereafter, the screws 14 and 15 are put in place and tightened.

In starting the motor, the operator actuates the starting button or pedal, not shown, thereby moving the plunger to the left as shown in the drawings. The first movement of the plunger to the left slides the gear 19, which is always in mesh with the pinion 18 on the end of the starting motor shaft 17, to the left until the pinion 21 begins to mesh with the flywheel teeth or butts against them. If the pinion 21 meshes with the teeth of the flywheel gear, further movement of the plunger to the left causes the switch-operating member 27 to push down the slide 32 and close the starting switch, causing the starting motor to rotate the gears and turn over the engine. As soon as the engine begins to operate under its own power and its speed increases so that the speed of the pinion 21 is greater than the speed of the gear 19, the roller clutch disconnects so that the gear 19 and starting motor will not be driven by the engine. In case the teeth of the pinion 21 strike against the sides of the teeth of the flywheel so that the pinion 21 cannot slide any farther to the left, the spring 26 is compressed, allowing continued movement of the switch-operating member 27. When the plunger has moved far enough to close the starting motor switch, the starting motor begins to revolve, and the first of its movement turns the pinion 21 slightly, so that the teeth of this pinion no longer strike against the sides of the flywheel teeth. As a result, the pressure exerted by the spring 26 then pushes the pinion into mesh with the flywheel and the engagement of the gears is effected. It will be seen that all the difficulty resulting from interference between the teeth of the sliding pinion and flywheel is effectively obviated, and it is practically certain that the teeth of the slidable pinion will be caused to mesh with the flywheel gear at once.

What we claim is:

1. In combination with the crank case and flywheel casing of an internal combustion engine, a flywheel within said casing provided with gear teeth, a train of gearing within said flywheel casing, a base, a starting motor mounted on said base exterior to said flywheel casing, said starting motor being connected to said train of gearing, a switch and mechanism within said base to actuate the switch and connect said starting motor to the flywheel through said gear train.

2. In combination, the flywheel and flywheel casing of an internal combustion engine, a starting motor, a base therefor, a switch for the starting motor, slidable gearing to connect the starting motor and the flywheel, and slidable plunger assembly extending into the flywheel casing and the base and movable to operate the starting motor switch and to slide the gears into engagement with the flywheel.
3. In combination, the flywheel and flywheel casing of an internal combustion engine, a starting motor, a base therefor, a switch for the starting motor, slidable gearing to connect the starting motor and the flywheel, and a slidable plunger assembly including a spring, said plunger extending into the flywheel casing and the base and movable to operate the motor switch and to slide the gears into engagement with the flywheel by exerting yielding pressure through said spring.
4. In combination, the toothed flywheel and flywheel casing of an internal combustion engine, a base for the starting motor, a starting motor located on the base and having its shaft extending into the flywheel casing, a pinion on the shaft in the flywheel casing, a slidable gear and pinion movable to connect the starting motor shaft with the toothed flywheel, a starting switch for the starting motor located in the base, and a slidable plunger assembly including a spring, a bushing and a switch actuating member, said plunger forming a support for the slidable gear and pinion and acting through said spring to move the gear and pinion yieldingly toward said flywheel.
5. In combination, the toothed flywheel and flywheel casing of an internal combustion engine, a base for the starting motor, a starting motor located thereon and having its shaft extending into the flywheel casing, a pinion on the shaft in the flywheel casing, a slidable gear and pinion movable to connect the starting motor shaft with the toothed flywheel, a starting switch for the starting motor located in the base, a slidable plunger assembly extending through the flywheel casing and supporting the gear and pinion within it, said assembly including a spring and a switch actuating member, and said parts being arranged so that the sliding of the plunger will move the gear and pinion yieldingly into contact with the side of the flywheel gear before the starting motor switch is closed.
6. In a self-starter gearing, an axially concentric gear and pinion connected by a roller clutch, a bushing forming a bearing therefor, a plunger slideable in the bushing and forming a support for the parts, a switch actuating member on the plunger, a spiral spring surrounding the plunger and bearing against the bushing, a collar, and detachable means securing the collar to the bushing adjacent the gear and pinion.

In testimony whereof we affix our signatures.

RALPH H. WHISLER.
STUART G. BAITS.
